(57) **CLAIM**

The ornamental design for a dispenser, as shown and described.

DESCRIPTION

FIG. 1 is an isometric view of a top, front, and right side of an ornamental design for a dispenser;

FIG. 2 is a front elevational view of the dispenser of FIG. 1; FIG. 3 is a rear elevational view of the dispenser of FIG. 1; FIG. 4 is a right side elevational view of the dispenser of FIG. 1;

FIG. 5 is a left side elevational view of the dispenser of FIG. 1;

FIG. 6 is a top plan view of the dispenser of FIG. 1; and, FIG. 7 is a bottom plan view of the dispenser of FIG. 1.

The dash-dot-dash-dot lines depicted in FIGS. 1, 2, and 6 illustrate an unclaimed interior portion of indeterminate size and shape. The dash-dash-dash lines depicted in FIGS. 1-7 are for the purpose of illustrating environmental structure and form no part of the claimed design.
